UNITED STATES PATENT OFFICE.

ALFRED KANE, OF NEW YORK, N. Y.

RADIATOR-CAP LIGHT.

Application filed May 25, 1923. Serial No. 641,436.

To all whom it may concern:

Be it known that I, ALFRED KANE, a citizen of the United States, residing at New York, in the county of New York and State of New York, have invented new and useful Improvements in Radiator-Cap Lights, of which the following is a specification.

This invention relates to improvements in radiator cap means and one of the objects of the invention is to provide a small lamp adapted to be placed on the filling spout of the radiator.

Another object of the invention is to provide a cylindrical screw threaded lower part 15 on the lamp for closing the filling spout and replacing the ordinary closing cap.

The invention also consists in certain other features of construction and in the combination and arrangement of the several 20 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a fragmentary side view showing my invention in use.

Figure 2 is a front view of the lamp;

Figure 3 is a section on line 3—3 of Figure 2.

Figure 4 is a view showing the arrangement of the conductor.

In these views 1 indicates the body of the lamp which is of substantially semi-cylindrical form. The bottom of the lamp is provided with an extension 2 which is screw 40 threaded so as to engage the screw threads of the filling spout of the radiator as shown in Figure 1 and at the top of this extension is a corrugated ring 21 for facilitating the screwing and unscrewing of the device on the spout. In using the device the ordinary filling cap is removed and the device forming the subject matter of my invention substituted therefor. The flat face of the casing is formed of a glass plate 3 which is held in place by forming channels 4 adjacent the edges of the casing to receive said plate. These channels pass through the upper end of the lamp casing so that the glass plate may be inserted and after said 55 plate is inserted the flaps 5 are bent over to hold the plate in place. An opening

is formed in each side of the casing and these openings may be closed by colored lens 6. An electric lamp socket 7 is suitably connected to the rear wall of the casing to receive the lamp 8 and a plug 9 is adapted to engage said socket in the usual manner. This plug has the ends of the conductors secured thereto so as to carry the current to the lamp. These conductors 60 are adapted to be electrically connected with a battery or other source of supply, and are enclosed in a flexible metallic cable adapted to be passed under the hood of the automobile as clearly shown in Figure 1 of 70 the drawings. An ornament such as the eagle 12 may be connected with the top of the casing and an opening 13 formed in said top to permit the light to pass from the casing on to said ornament. The interior 75 wall of the casing may be provided with suitable reflecting material or it may be polished to act as a reflector for the light.

It will be thus seen that I have provided a neat and effective ornament, which may 80 be applied to any car by simply removing the cap of the filling spout and substituting the device. The ornament at the top of the casing will be illuminated and the colored lens will add to the attractive appearance. 85 When the car is being used on a well lighted street or is parked the front lamps may be extinguished as my device will furnish sufficient light in such cases.

It is thought from the foregoing description that the advantages and novel features of my invention will be readily apparent.

I desire it to be understood that I may make changes in the construction and in the combination and arrangement of the several 95 parts, provided that such changes fall within the scope of the appended claims.

What I claim is:—

1. A device of the class described comprising a casing, an internally screw 100 threaded extension formed on the lower end of said casing and adapted to co-act with the threaded portion of a filler spout on the radiator of an automobile, a transparent panel mounted in the front wall of said casing, a pair of colored lenses mounted in the side walls of said casing and arranged diametrically opposite each other, a lamp mounted in the rear wall of said casing, a transparent panel mounted in the top wall 110 of said casing and an ornament mounted on the top wall and to the rear of said trans-

parent panel, and extending over the same, whereby the light from said lamp will pass through said panel for illuminating said ornament.

5. 2. A device of the class described comprising a semi-circular casing having its flat face open and a cylindrical extension at the bottom thereof, said extension being screw threaded for engaging the filling 10 spout of the radiator, a transparent plate closing the opening, the top of the casing having an opening therein, an ornament on the top in the rear of said opening and a lamp in said casing, the rays of which will 15 pass through the transparent plate in the front of the casing and through the opening in the top to illuminate the ornament.
3. A radiator cap light of the class described comprising a lamp body formed with

an open front and with openings in the sides 20 thereof and having the side edges at the front provided with confronting channels, a screw threaded extension on the bottom of said body for engaging the screw threads 25 of the radiator filling spout, a transparent plate carried by the front side of said body and mounted in said channels, colored lenses inserted in the openings in the sides of said casing, a lamp on the rear wall of said casing, and an ornament arranged on the top of 30 said casing, the top wall of said casing having an opening therein to permit the light to pass through and illuminate said ornament.

In testimony whereof I have affixed my 35 signature.

ALFRED KANE.
